2 SHEETS—SHEET 2.

UNITED STATES PATENT OFFICE.

JOHN PETER WEIS, OF NYACK, NEW YORK, ASSIGNOR OF ONE-HALF TO METROPOLITAN SEWING MACHINE CORPORATION, OF DOVER, DELAWARE, A CORPORATION OF DELAWARE.

SEWING MACHINE.

Original application filed October 16, 1914, Serial No. 867,005. Patent No. 1,348,526, dated August 3, 1920. Divided and this application filed January 2, 1919. Serial No. 269,276.

To all whom it may concern:

Be it known that I, JOHN PETER WEIS, a citizen of the United States, residing at Nyack, in the county of Rockland and State 5 of New York, have invented certain new and useful Improvements in Sewing Machines, of which the following is a specification.

This invention relates to sewing machine heads and stitch-forming mechanism therein. Its objects are to produce a stitch-forming mechanism capable of high speed carried in a head specially constructed for easy working assemblage with the stitch-forming mechanism and itself adapted for 15 high speed service.

In the accompanying drawings forming a part hereof,

Fig. 1 is a vertical central section of a sewing machine head embodying this invention; and Figs. 2, 3, 4, 5 and 6 are views of the pump and container.

The present application is a division of my application Serial No. 867,005, for sewing machine and cutting mechanism therefor, filed October 16, 1914, on which Letters Patent No. 1,348,526 were issued on August 3, 1920, and embraces subject-matter shown in said application and also in my application Serial No. 94,355, filed April 29, 1916, 25 for stop motion on which Letters Patent No. 1,352,333 were issued on September 7, 1920, and in my application Serial No. 94,354, filed April 29, 1916, for lubricating system and sewing machine construction on which 30 Letters Patent No. 1,348,527 were issued on August 3, 1920, the two latter applications being divisions of my said application Serial No. 867,005.

In the drawings, the sewing machine head 40 comprises an upper horn A, an under horn A', and a connecting trunk a, the horns and trunk having communicating chambers. The outer wall of the trunk comprises an inwardly projecting boss a' in the inward end 45 of which stop-motion members are arranged in operative relation to the rear end of the top or needle-bar drive-shaft. The upper side of the upper horn A is provided with a covered opening at a² for access to the chamber of the trunk, and the outer end wall is provided with an opening a³ through which the lubricant is poured into an oil container carried by a lower part of the trunk. The

rear wall of the trunk is also provided with a covered opening a⁴ into a lengthwise-extending chamber of the boss a' for observation of the lubricant through the transparent cover a⁵ in the chamber of the boss a', the rearward portion of such chamber forming an oil space and the forward portion forming a housing. The top drive-shaft and the looper shaft hereinafter described are both tubular and each is enclosed between its ends for the greater part of its length in tubes hereinafter described, which are centered and held in the lengthwise-extending chambers of the horns by set-screws a⁶ through the horns and impinging on the outer surfaces of the tubes.

The oil reservoir 1 carried by the lower 70 part of the trunk is supplied with oil through the opening a⁸, the oil being poured into the drip-pan 2 which covers the top of the oil reservoir and also projects laterally thereof in the direction of and below the 75 under horn A'. The trunk is open at a' on its under side. The drip-pan is provided over the rearward side of the reservoir with a depressed perforated bottom portion forming an oil strainer 3. From the drip-pan 80 the oil flows into a compartment 4 at the rearward side of the reservoir which is interiorly provided with parallel vertical walls 5 that are spaced apart, the space containing filtering material 6. The walls 5 85 are numerously perforated at 7 and the oil flows from compartment 4 through the perforations in the walls 5 and the filtering material between them into the compartment 8 wherein an oil pump is located. The drip-pan has a vertically walled opening 9 90 through it for passage of a belt B that drives the pump and also drives the top or needle shaft of the sewing machine. The induction tube 10 of the pump extends downwardly towards the bottom of compartment 8 and the eduction tube 11 extends upwardly from the pump through the chamber of the trunk to conduct the pumped oil to the oil conduit 12 in the top of the boss a'. The pump comprises two small thin spur gears 13 and 13^a, one of the gears being provided with trunnions 14 which are journaled in the side walls of the pump casing, and the other gear being fixed on a shaft 15 which is journaled 100 in the side walls of said casing and has one

of its ends extended to receive the driving pulley 16. The pump casing comprises a recessed block and a cover therefor. The block has an elongated recess 17 of a depth 5 of the thickness of the gears which are the same thickness. The recess 17 has a length sufficient to receive the two gears when intermeshed. The block is provided with alined holes which lead from opposite sides of the 10 recess 17. One hole is under and the other above the gears, for reception respectively of the pump induction and eduction tubes 10 and 11 which are alined with the intermeshing peripheries of the two gears. The outward 15 face of the block has an annular recess 18 the botttom of which is flush with the outward surfaces of the intermeshing gears. The outward face of the block has another annular recess 19 concentric with, but of 20 greater diameter than recess 18. The recess 19 is enclosed by the margins 20 of the outward face of the block which is indicated by 21. The cover is formed of a disk having on its inner face an annular projecting boss 22 25 of a diameter to fit into a recess the bottom of which is indicated by 18 with the inward face of the boss close up to the outward faces of the intermeshing gears. The cover is also provided with an annular flange 23 which 30 fits into the recess 19 and is fixed air-tightly thereinto. Boss 22 is provided on its inner face with bearing holes 24 which extend only partway through the boss 22 and which support, one an end of the gear shaft 15, and 35 the other a trunnion of the gear 13^a. These bearing holes 24 are blind holes for insurance of air-tightness of the pump. The pump gears 13 and 13^a are shown full size, and so also is the entire pump structure in 40 Figs. 2 and 6. It has been found in practice that a pint of oil can be passed through the sewing machine every three minutes by means of this pump which is practically efficient in keeping some oil-containing parts 45 constantly lubricated by oil spray produced by either the centrifugal or vibrating forces of the high-speed parts.

The top drive-shaft 25 is bored throughout its length to form an oil conduit 26, the 50 rearward end of this shaft projecting into the oil chamber 27 in the boss a', such chamber being supplied from the eduction tube 11 through the conduit or port 12 in the upper side of the boss a'. The front end 55 of the conduit 26 is plugged at 28. The front end of the top shaft has an exteriorly reduced portion 29 and in this portion its wall is drilled at 30 to form oil conduits leading from the conduit 26 and permitting 60 the passage of oil therefrom to the front bearing 31 of this top shaft; the bearing 31 being fixed in an enclosing tube 32 which is held in place by the set-screws a⁶. The enclosing tube 32 projects forwardly beyond 65 the front wall of the front bearing 31 and

forms a housing 33 for the needle-driving crank 34 fixed on the projecting end of the shaft 25. At its rear end, shaft 25 is fixedly united to a tubular ball crank member 25^a which forms a rearward prolongation of the 70 top drive-shaft. The member 25^a is formed with two ball cranks 35 which are each drilled at 36 to form oil conduits from the lengthwise tubular chamber of the member 25^a to the bearings 38, one at the upper end of a connecting rod 39 and the other at the upper end of a connecting rod 39^a. The tubular ball crank member 25^a has its bore in alignment with the conduit 26 of the shaft 25 so that the conduit 26 extends from its 80 front plug 28 rearwardly to the extreme outer end of such ball crank extension of the top drive-shaft. Said member 25^a is a rearward prolongation of the top or needle drive shaft, and forms a tubular ball crank 85 member as stated; on it there is mounted, within the chamber of the trunk, a top shaft drive member shown as a pulley 37 for the pump and top shaft driven belt, B. Said prolongation or member 25^a also carries a 90 stop motion mechanism 46 which forms the subject matter of my application Serial No. 94,355, filed April 29, 1916, as a division of my application Serial No. 867,005, filed October 16, 1914. The stop motion mechanism 95 is also within the trunk chamber and encircles the member 25^a and has structural portions located in an annular recess in the forward end of the boss a', the forward end of the tubular portion of the boss having its 100 under wall recessed at 8^a for entrance of a stop finger 64^a for the stop motion which, with other parts of a stop motion control lever indicated in part by 64^b are also located within the chamber of the trunk. The 105 oil chamber 27 of the boss has an oil-escape port 83 and, the bore 84 of the member 25 communicates at its rear end with the chamber 27. The rear end of the bore in said extension opens into oil chamber 27. Surplus 110 oil from the ball cranks 35 and the bearings 38 flows down the connecting rods 39 and 39^a to the respective ball bearings 40 and 41 thereof at their lower ends. The wall of the conduit 26 within the enclosing end of 115 its said rearward prolongation 25^a is bored at 42 and the enclosing forward end of the member 25^a is coincidently bored at 43 to form conduits from the conduit 26 to the rearward bearing 44 of the top drive-shaft 120 25, this rearward bearing being fixed in the rear end of the enclosing tube 32. The side wall of the front end of conduit 26 just rearwardly of the plug 28 is perforated at 45 exteriorly of the front bearing 31 and within 125 the housing 33 to form an oil conduit leading from conduit 26 into an oil conduit 47 formed by drilling the needle - driving crank 34.

Conduit 47 discharges oil on the front ad- 130

vancing surface of the crank at one side of the crank pin 48 and such oil flows down the advancing surface of the rotating crank to and lubricates the crank pin in its bearing 49 which is formed in the upper end of the needle-driving link 50. Some of this oil flows out on the crank, and going to the crank-pin bearing, is whirled off by centrifugal force and caught within the housing 33; and other of the oil coming to the crank pin bearing flows down the needle link 50 to and lubricates the connection 51 of the needle link with the needle holder 53. This oil escaping at the connection 51 finds its way to the needle-holder guide-bar 54 and needle-holder ears 55 that reciprocate vertically in the groove 56 of the needle-holder guide 57. The oil passing through the conduit 47 is forced thereinto by centrifugal force and it is found in practice that the amount of oil finally coming to the needle holder and needle-holder guide is, while sufficient for lubrication purposes, negligible so far as any deposit of oil on the goods is concerned.

The shank of the needle-holder guide 57 is formed with an oil conduit 58 which extends downwardly to near the bottom of the needle-holder guide-bar 54, the wall of conduit 58 being perforated at 59 to permit escape of oil to the outer surface of the needle-holder guide-bar.

The top-shaft-enclosing tube 32 at its forward end and lower portion has a transverse web 60, or in other words the housing 33 has such transverse web which forms a dam to hold back in the housing any oil if it drops to the bottom thereof. The front bearing 31 is formed on its under side with a lengthwise conduit 61 that conducts oil rearwardly into the tube 32 from the bottom of the housing 33; and such oil flows rearwardly through the conduit 61 along the bottom of the tube 32 to oil-conduit 62 which is formed in the bottom of the rearward bearing 44 of the top shaft.

The rear end of conduit 62 discharges within a housing or cap 63 which is open at its under side. This cap encloses the rearward end of the tube 32 and has at its rear end an opening for reception of the flanged end of the pulley hereinafter described. The under sides of the housing or cap 63 are curved laterally inwards at 64 giving the housing 63 a trough shape along its bottom both lengthwise and transversely thereof. Oil flowing into the chamber of the housing from conduit 62 flows along the adjacent edges 65 thereof to the drip point 66 which is directly over a V-shaped oil-receiving space 67 in the upper side of a bell crank 68 one arm of which terminates in a ball 41^a working in the ball bearing 41, and the other arm of which 65 terminates in a ball 69 which is entrant

in the looper shaft. Oil so falling into the space or opening 67 oils the crank of the bell crank journal and flows down the lower bell-crank arm to its end 69 which is within the rear end of the lengthwise-chambered looper-shaft 70, the upper side of this looper shaft having a slot 70^a through which the lower end of the lower arm of the bell crank extends. Oil collecting in the chamber of the looper shaft at the lower end of the lower arm of the bell crank, flows forwardly through conduits 71 in the plug 72 which is slidable in the chamber of the looper shaft just forwardly of the lower end 69 of the lower member of the bell crank. The oil flowing through these conduits 71 passes the coil spring 73 which is mounted between the slideable plug 72 and a forward fixed plug 74 that forms an abutment within the chamber of the looper shaft for the forward end of the coil spring 73. The plug 74 is formed with conduits 75 whereby the oil flows therethrough and forwardly through the chamber of the looper shaft to the front end portion thereof, and thence through openings 76 in its side wall for oiling its front bearing 77; thence some of the oil escapes into the annular recess 78 on the front face of the bearing 77, from the lower portion of which recess 78 a conduit 79 extends downwardly and rearwardly into the chamber of a tube 80 which encloses a greater part of the length of the looper shaft, and in the front end of which the front bearing 77 of the looper shaft is fixed. The rear bearing 77^a of the looper shaft is fixed in the rear end of the tube 80 which is centered in the chamber of the lower horn A' by set-screws a^a similarly to the centering and fixing of the enclosing tube 32 for the top drive-shaft. The rear bearing 77^a is provided with a rearwardly and downwardly inclined conduit 81 which discharges into the forwardly projecting portion of the drip-pan, the bottom of which is inclined rearwardly to the oil strainer 3. The looper shaft has its rearward portion within the rearward bearing 77^a provided with oil conduits 76^a for lubricating the looper shaft in its rearward bearing.

The connecting rod 39 leading to the bell crank 40^a at the rear end of the looper shaft, serves to oscillate the looper shaft, the crank 40^a projecting from a plug 82 fixed in the rear end of the looper shaft.

The connecting rod 39^a at its lower end cooperates with the ball 41^a on the outer end of the upper arm of the bell crank 68 and reciprocation of this connecting rod 39^a, by means of the bell crank, the movable plug 72, the spring 73, and the fixed plug 74, secures endwise reciprocation to the looper shaft in its front and rear bearings 77, the 130

forward movement of the looper shaft being against the resistance of the spring 73 which is a mere take-up spring for wear on the plugs 72 and 82 and the ball 69. 5 Spring 73 is under heavy tension and the reciprocation of the looper shaft is positive in each direction. The ball connections formed by the ball cranks 35 and their bearings 38 and by the bearings 40 and 41 and the balls 40^a and 41^a and by the ball 69, secure easy actuation of the connecting rods 39 and 39^a for the rocking and endwise reciprocatory movements of the looper shaft.

10 15 What I claim is:

1. A sewing-machine head having a chambered trunk, and lengthwise chambered upper and under arms; a hollow tube in each arm; means for locating and holding the tube in each arm; a needle drive shaft in the tube in the upper arm; a looper shaft in the tube in the under arm; and, in the chamber of the trunk, mechanism for driving the drive shaft and other mechanism for 20 25 rocking and giving endwise reciprocation to the looper shaft.

2. In the structure of claim 1, the bearings for the drive shaft being mounted in the upper arm tube and the bearings for the looper shaft being mounted in the under arm tube.

3. In the structure of claim 1, the mechanism for actuating the looper shaft comprising a pivoted bell crank operatively connected at one end with the looper shaft; a crank rod operatively connected at its other end to a crank on the drive shaft; and a connecting rod operatively connected at one end to a crank on the drive shaft and at its 35 40 other end to a crank on the looper shaft.

4. In the structure of claim 1, the trunk chamber having a rear end bearing for the drive shaft and the drive shaft having its rear end journaled in said bearing; and a power-driving device on the drive shaft between said bearing and the rear end of the 45 upper arm tube.

5. In the structure of claim 1, the trunk chamber having a rear end bearing for the drive shaft and the drive shaft having its rear end journaled in said bearing; and a power driving device on the drive shaft between said bearing and the rear end of the upper arm tube; the rear end of the upper 50 55 arm tube and said power driving device being spaced apart; the drive shaft having two adjacent crank members in said space; and a connecting rod for each of said members for rocking and reciprocating connection with the looper shaft.

6. In a sewing machine, the combination of a needle drive shaft provided with a pair of ball cranks; a looper shaft provided with a ball crank and with a lengthwise-extending slot; a connecting rod between one ball

crank of the needle drive shaft and a ball crank of the looper shaft; a pivoted lever having ball ends; a connecting rod between the other ball crank of the needle drive shaft and one end of said lever, the under end of which is located in said slot in the looper shaft; and slidably mounted in a chamber of the looper shaft a slidable plug against which said under-end of the lever abuts; a spring in said chamber against which the 70 75 plug abuts, and an abutment for the spring.

7. A sewing machine head comprising, in combination, a lengthwise chambered upper arm and a lengthwise chambered under arm, said arms being connected by a vertical 80 chambered trunk; a lengthwise extending, tubular, top drive shaft support provided with bearings for the drive shaft; a top drive shaft journaled in the bearings; means for adjustably positioning said tubular support 85 in the chamber of the upper arm spacedly apart from the wall of the chamber; a lengthwise extending under, tubular, looper shaft support provided with bearings for a looper shaft; means for adjustably positioning the under tubular support in the chamber of the under arm spacedly apart from the wall of such chamber; a looper shaft journaled in the bearings in the under tubular support; and looper actuating mechanism 90 95 operatively connecting the drive shaft with the looper shaft.

8. A sewing machine head comprising, in combination, a lengthwise chambered upper arm and a lengthwise chambered under arm, 100 said arms being connected by a vertical chambered trunk; a lengthwise extending, tubular, top drive shaft support provided with bearings for the drive shaft; a top drive shaft journaled in the bearings; means 105 for adjustably positioning said tubular support in the chamber of the upper arm spacedly apart from the wall of the chamber; a lengthwise extending under, tubular, looper shaft support provided with bearings 110 for a looper shaft; means for adjustably positioning the under tubular support in the chamber of the under arm spacedly apart from the wall of such chamber; a looper shaft journaled in the bearings in the under 115 tubular support; and looper shaft actuating mechanism operatively connecting the drive shaft with the looper shaft; the top drive shaft and the looper shaft actuating mechanism connected with the top drive shaft 120 being located within the chamber of the trunk, and the looper actuating mechanism comprising means to give the looper shaft both a rocking movement and an endwise reciprocating movement.

9. In the structure of claim 1, the mechanism for actuating the looper shaft comprising a pivoted bell crank operatively connected at one end with the looper shaft; a crank rod operatively connected at its 125 130

- other end to a crank on the drive shaft; and a connecting rod operatively connected at one end to a crank on the drive shaft and at its other end to a crank on the looper shaft; and take-up means within the looper shaft for engagement with the entrant arm of the bell-crank lever.
10. In the structure of claim 1, an oil container and pump supported by the trunk below the looper shaft and rearwardly of the rear end of the looper shaft; a power driving device on the drive shaft; and a power driver for the pump, such driver being located under said power driving device; and a belt from the shaft driver to the pump driver.
11. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; said chambered boss having a rear end flange, and the trunk wall having an opening for reception and fixture of the flanged boss.
15. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; the pump shaft being parallel with the drive shaft; the alined drivers being at right angles to the drive and pump shafts; and the pump shaft having a fixed spur gear in mesh with a spur gear carried within the container on a shaft parallel with the pump shaft.
20. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; the pump shaft being parallel with the drive shaft; the alined drivers being at right angles to the drive and pump shafts; and the pump shaft having a fixed spur gear in mesh with a spur gear carried within the container on a shaft parallel with the pump shaft.
25. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; the pump shaft being parallel with the drive shaft; the alined drivers being at right angles to the drive and pump shafts; and the pump shaft having a fixed spur gear in mesh with a spur gear carried within the container on a shaft parallel with the pump shaft.
30. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; the pump shaft being parallel with the drive shaft; the alined drivers being at right angles to the drive and pump shafts; and the pump shaft having a fixed spur gear in mesh with a spur gear carried within the container on a shaft parallel with the pump shaft.
35. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; the pump shaft being parallel with the drive shaft; the alined drivers being at right angles to the drive and pump shafts; and the pump shaft having a fixed spur gear in mesh with a spur gear carried within the container on a shaft parallel with the pump shaft.
40. In the structure of claim 1, the trunk chamber having a rear end bearing for the drive shaft and the drive shaft having its rear end journaled in said bearing; and a power driving device on the drive shaft between said bearing and the rear end of the upper arm tube; said bearing being mounted in a horizontally chambered boss carried by the trunk, the bearing extending from the front end of the chamber of the boss part way to its rear end, leaving a chamber between the bearing and the rear wall of the trunk; the wall of such chamber being oriented for reception of an oil conduit; and the wall of the boss opposed to the bearing together with the bearing being recessed for reception of stop-motion members; and such members; the pump shaft being parallel with the drive shaft; the alined drivers being at right angles to the drive and pump shafts; and the pump shaft having a fixed spur gear in mesh with a spur gear carried within the container on a shaft parallel with the pump shaft.

In testimony whereof I have hereunto set my hand this 27th day of December, 1918.

JOHN PETER WEIS.
